INSULATOR

George A. Mead, Mansfield, Ohio, assignor to The Ohio Brass Company, Mansfield, Ohio, a corporation of New Jersey

Application January 16, 1937, Serial No. 120,949

5 Claims. (Cl. 174—30)

My invention relates to electric insulators for supporting electrical conductors and to a method of manufacturing the same, and one of the objects is to provide an insulator which is practically free from radio interference especially at voltages above that of the rated voltage of the insulator and an improved method of manufacturing the same.

Another object is to provide an insulator forming a closed receptacle free of metallic parts therein and which is filled with a gaseous dielectric and having improved means for sealing the receptacle without the use of organic materials such as rubber, phenolic condensation products and etc. to prevent the escape of the gas.

My invention resides in the new and novel construction, combination, and relation of the parts hereinafter described and shown in the accompanying drawing and in the steps of manufacture disclosed in the specification, and particularly set forth in the claims.

In the drawing:

Fig. 1 is a side view in partial section.

Fig. 2 is a transverse sectional view on the line 2—2 of Fig. 1.

Figs. 3 and 4 are modified forms of joint construction.

My invention is applicable to insulators for various purposes and particularly to what are known as line-post insulators that is an insulator arranged at one end to be mounted on a support and having means at the other end to receive a conductor.

I provide a hollow member preferably of porcelain although for some purposes compounds using synthetic resins may be used. The hollow member is filled with a gaseous dielectric and then sealed tight.

An insulator of the hollow type if not sealed tightly will take on a film of moisture over its inner surface which will cause a discharge within the insulator which will in turn produce a noisy insulator and therefore a source of radio interference.

45 A hollow insulator which is sealed tight with dead air within the insulator is an improvement as compared with one not sealed tightly, but for the best results I replace the normal air with a dry gaseous dielectric such as carbon dioxide or nitrogen at atmospheric pressure or under low pressure.

Under some conditions air within the insulator may be withdrawn leaving a more or less partial vacuum.

55 In the preferred embodiment of my invention, I

provide a corrugated recessed porcelain member 1 closed at one end and open at the other. The closed end is provided with a line wire-groove 2 and a flange 3 for convenience in securing a tie wire to the insulator for holding the line wire in place. The closed end may have a metal cap if desired secured thereto as by cement for holding the line wire or for other purposes.

The open end of the member 1 is closed by means of a disc 4 of porcelain secured in position by interposed fused material so as to form a sealed joint 5 between the disc and member 1. Secured upon the sealed end of member 1 by means of cement 6 is a mounting casting 7.

The disc 4 is provided preferably with two through openings each having a relatively large portion 9 and a smaller portion 10. Mounted in the portion 9 by means of cement 11 is a valve body 12 and a valve 13 for closing the openings 8 in the valve body. A small spring 14 holds the valve against one of its seats depending upon whether the air is being exhausted or replaced with a dry gaseous dielectric; the valve 13 in Fig. 1 is shown for retaining gas within the hollow 15 of the receptacle.

The valve and valve body may be of metal or of glass or other suitable material. If of metal it is sealed permanently at 16 by means of solder; if of glass it may be sealed with cement. The valve 13 is merely to close the passage through the disc 4 and valve body 12 while the passage is being sealed permanently.

In replacing the air with a gas, the source of gas supply is contacted with one of the valve openings 8 which will force the valve 13 off its seat while the operator holds the other valve 13 off its seat by means of a suitable tool or wire to allow the air to be forced out as the gas enters.

In the manufacture of my invention the parts 1 and 4 are shaped from dry unfired or plastic porcelain body as is well known to those skilled in the art and in the latter case the body is then allowed to dry; the parts are then given a coating of liquid glaze and when dry the parts 1 and 4 are placed together in their relative positions. 45 If the glaze applied to the parts is not enough to seal the joint 5 additional glaze material may be applied at the joint after parts are assembled but before firing. Glaze generally is a porcelain body in a liquid form.

The parts are now placed in a kiln fired to the proper temperature to vitrify the members 1 and 4 and to melt the glaze. After the parts have been subjected to a proper temperature for a sufficient length of time the kiln and parts are al-

lowed to cool slowly and the glaze will solidify as the temperature in the kiln is reduced.

When the fired parts 1 and 4 are removed from the kiln the valve body 12 and valve 13 are cemented in position as by means of litharge and glycerin cement or other suitable cement.

I prefer to mount the valve in place and fill the hollow 15 of the receptacle with gas as soon as possible after removal from the kiln as the air within the insulator has been heated and expanded during the vitrifying period and a portion thereof forced out of the receptacle and hence the inner walls of the receptacle are in a dry condition.

15 If a metal valve is used the openings 8 may be closed by a drop of solder applied by a heated iron. If the valve is of glass or other non-metallic material a cement will close the openings.

The gas within the receptacle may be subjected to reasonably high pressure if required although as a rule only a few pounds above atmospheric pressure will suffice.

After filling the receptacle with gas or withdrawing the air from the receptacle the base 7 is cemented into position. When the insulators are to be used in the open or exposed to weather especially under fog conditions, Portland cement may be used mixed with a water repellent such as talc or soapstone or with emulsified asphaltum 30 which will render the cement waterproof.

In Figs. 3 and 4 I have shown modified constructions of the fused joint between the parts 1 and 4, however, I prefer the form of joint shown in Fig. 1.

35 Having described my invention, I claim:

1. An insulator comprising a porcelain shell having a perforation through the porcelain wall thereof, valve mechanism including a valve secured in said perforation to facilitate filling said shell with gas and for closing said perforation to prevent escape of said gas after filling and prior to sealing and supplemental means for sealing said perforation to retain said gas permanently in said shell notwithstanding any possible slow leak in said valve.

40 2. An insulator comprising a porcelain shell

member having an opening in the wall thereof, a porcelain closure sealed in place in said opening, said closure having a perforation therethrough, a valve body sealed in said perforation and having a valve opening therethrough, a valve for closing 5 said valve opening and supplemental means for sealing said valve opening.

3. An insulator comprising a hollow porcelain member having an opening in the wall thereof, a porcelain closure for said opening fused in place 10 therein, said closure having a pair of perforations therethrough, valve bodies cemented in place, one in each of said perforations for closing said perforations, valve openings in said valve bodies, respectively, valves for closing said valve openings 15 and supplemental means for sealing said valve openings.

4. A post insulator comprising a tubular, porcelain member integrally closed at one end thereof and open at the other end, a porcelain disc fused 20 in place in the open end of said member, said porcelain disc having a pair of perforations therethrough, valve bodies cemented in place, one in each of said perforations, said valve bodies having valve openings therethrough to permit gas 23 to be forced into the interior of said member through one of said openings while the gas in said member escapes through the other, valves for closing said openings respectively, supplemental means for sealing said valve openings to prevent slow leakage of gas past said valves and a metal fitting secured to said tubular member and overlapping said disc said fitting serving also as a reinforcement for the fused connection between 30 said tubular member and said disc.

35 5. An insulator comprising a porcelain shell having an opening in the wall thereof, a porcelain closure for said opening fused in place therein, said closure having a perforation therethrough, a metal valve body cemented in said 40 perforation and having a valve opening therethrough, a valve for closing said valve opening and a supplemental solder seal for said valve opening.

GEORGE A. MEAD.
